UNITED STATES PATENT OFFICE.

BERT C. CAREY, OF SIOUX CITY, IOWA, ASSIGNOR OF ONE-FOURTH TO FRANK P. BERGER AND ONE-FOURTH TO BAYTON F. CAREY, BOTH OF SIOUX CITY, IOWA.

CONCRETE MIXER.

Application filed November 21, 1921. Serial No. 516,577.

To all whom it may concern:

Be it known that I, BERT C. CAREY, a citizen of the United States, and a resident of Sioux City, in the county of Woodbury and State of Iowa, have invented certain new and useful Improvements in Concrete Mixers, of which the following is a specification.

My invention has for its object the production of an improved concrete-mixing device.

Another object of the invention is the production of a concrete-mixing device embodying a rocking mixing-container and improved means for preventing the entrance thereinto of large rock. Furthermore, the invention contemplates a concrete mixer embodying a rocking material container and means for preventing the entrance thereof into of large rock, and which means retains the rock and is so constructed that when the container is rocked to eject its contents into a receptacle, the large rock are dumped into the receptacle prior to the ejection of the mixed material.

These and other objects and advantages are successfully obtained in the embodiment hereinafter described, defined in the appended claims and illustrated in the accompanying drawing, which forms a part of this application and in which like characters of reference indicate corresponding parts in both views, of which:

Fig. 1 is a plan of a device constructed in accordance with the invention, parts being cut away, and

Fig. 2 is a fragmentary side elevation thereof.

While I have illustrated and hereinafter described the preferred embodiment of the invention, I would not be understood as being limited to such specific construction, for various alternations and modifications may be made in the details of construction and arrangement of parts herein disclosed without departing from the spirit and scope of the invention as defined in the appended claims.

Referring, now, to the illustrations, my improved device includes a supporting frame preferably including front and rear frame-members, 3, interconnected by end cross-members, 4, and supported by suitable legs, 5, at the corners. The frame supports a material-mixing receptacle, preferably com-

prising a sheet metal cylinder, 6, disposed horizontally within the frame and provided with heads, or end walls, 7. Extending coaxially through the receptacle is a shaft, 8, journaled in suitable bearings, 9, on the frame-members, 4. Within the receptacle the shaft carries radial arms, 10, disposed in different radial planes and adapted to agitate the material within the receptacle by rotation of the shaft, which may be actuated by a crank, 11, on the shaft, 8, or otherwise. The upper side of the receptacle is open, as at 12, and at the sides of the said opening, 12, the receptacle is formed with flanges, 13. To one end of the receptacle is secured a lever-arm, 14, which normally extends rearwardly and rests upon the adjacent frame-member, 3, and serves to rock the receptacle to dump the material therefrom, as will presently be made more clear.

I provide above the opening, 12, a swinging grate which serves to prevent entrance of large rock into the receptacle and retains them until the receptacle is dumped. The said grate comprises, preferably, a suitable shaft, 15, extending longitudinally of and adjacent the rear of the opening, 12, and journaled in suitable bearings, 16, carried by the receptacle. The shaft, 15, is provided with a series of spaced gate-bars, 17, which are curved downwardly, as at 18, to retain rock which are too large to pass between the bars and are retained thereby. At one end of the series of grate-bars is a straight bar, 19, which normally rests upon the adjacent flange, 13, to support the grate in its normal position. At the opposite end of the series the shaft, 15, carries an arm, 20, spaced above the bars, 17 and 19, and having a curved end, 21.

Obviously, the concrete materials are introduced in to the receptacle through the opening, 12, and as the previously stated, any large rock which might damage the agitating-means within the receptacle are retained by the grate. The material is then mixed through rotation of the shaft, 8, and then dumped from the receptacle by upward movement of the lever-arm, 14. The initial rotary movement of the receptacle in the act of dumping brings the grate to an inclined position, as indicated in dotted lines at 22, to permit the large rock to drop from the grate, in which position the curved end of the arm, 20, rests upon the front frame-

member, 3. Then, upon further rotary movement of the receptacle the said arm, 20, slides upon the frame-member, 3, and contacts with the shaft, 15, to lift the grate 5 from the opening, 12, permitting the unobstructed dumping of the material from the receptacle and onto the rock previously dumped from the grate. Thus, it will be seen, large rock are retained by the grate, 10 during the mixing process, and the mixture is then dumped directly on the rock. Extending across the rear periphery of the receptacle is an angle-iron, 23, the end portions of which project over the supporting 15 frame, the said angle-iron serving to stiffen the receptacle, and its projecting ends serve as stops which engage the frame members, 4, to limit the forward rocking movement of the receptacle. Obviously, the receptacle and its grate are restored to their normal positions by rocking the receptacle rearwardly through the medium of the lever-arm, 14.

Having thus described my invention, 25 what I claim as new and desire to secure by Letters Patent of the United States, is:

1. A concrete mixer embodying a mixing receptacle having an upper opening and mounted to rock between normal and 30 dumping positions, a guard grate normally extending across said opening and hinged to the receptacle to swing from the opening, and an element fixed, with respect to the receptacle, to be positively engaged by the 35 grate when the receptacle is swung to dumping position, to swing the grate from the opening.

2. In a concrete mixer a suitable support, 40 a mixing receptacle having an upper opening and mounted on the support to rock between normal and dumping positions, a guard-grate normally extending across said opening and hinged to swing from the opening, and means governed by movement 45 of the receptacle to its dumping position

and coacting with the support to swing the guard-grate from the opening.

3. A concrete mixer embodying a mixing receptacle having an upper opening and mounted to rock between normal and dumping 50 positions, a guard-grate normally extending across said opening and including a rock-shaft positioned adjacent one side of the opening, and a series of spaced bars carried by the shaft and normally extended 55 across the opening, and an element fixed with respect to the receptacle to be positively engaged by the grate when the receptacle is swung to dumping position, to swing the grate from the opening.

4. In a concrete mixer a suitable support, a mixing receptacle having an upper opening and mounted on the support to rock between normal and dumping positions, a guard-grate normally extending across said 60 opening and including a rock shaft positioned adjacent one side of the opening, and a series of spaced bars carried by the shaft and normally extended across said opening, and means governed by movement of the 65 receptacle to its dumping position and coacting with the support to swing the guard-grate from the opening.

5. In a concrete mixer a suitable support, 75 a mixing receptacle having an upper opening and mounted on the support to rock between normal and dumping positions, a guard-grate normally extending across said opening and including a rock shaft positioned adjacent one side of the opening, and 80 a series of spaced bars carried by the shaft and normally extended across said opening, and an arm on the rock-shaft engageable with the support when the receptacle is moved to its dumping position, to turn the 85 rock-shaft and thereby move the said bars from the opening.

In testimony whereof, I have hereunto set my hand this 5th day of May, 1921.

BERT C. CAREY.
